UNITED STATES PATENT OFFICE

2,082,901

NAIL PULLER

Carl Palmu, Maple, Wis.

Application May 12, 1936, Serial No. 79,375

3 Claims. (Cl. 254—22)

This invention relates to devices for extracting or pulling nails, spikes or the like and the primary object of the invention is to provide a device of this character characterized by extreme 5 simplicity of construction and yet will at the same time prove efficient for extracting or pulling nails of various sizes and also such nails that are either by structure without enlarged heads or from which the heads have been sheared.

10 The invention together with its objects and advantages will be best understood from a study of the following description taken in connection with the accompanying drawing wherein:—

Figure 1 is a side view of the nail puller.

15 Figure 2 is a top plan view of the nail engaging end of the tool and

Figure 3 is a view partly in section and partly in elevation of the tool at the nail engaging end thereof.

20 In accordance with the present invention the tool comprises a handle 5 formed of iron or other suitable material and which is preferably equipped at one end as at 6 for use as a prying bar for prying open the lids of boxes or the like.

25 At its respective opposite end the bar 5 is formed with an integral claw nail-starter 7 that is curved to present a convex fulcrumed edge 8 and a sharpened end edge 9 which latter engages the shank of the nail at one side of the latter.

30 The end 9 of the claw 7 is adapted to cooperate with a jaw 10 formed integrally with one end of a yoke or loop 11 pivoted on the head or claw 7 and which has spaced parallel sides terminating at the end thereof remote from the jaw 10 in inwardly directed pins 12 journaled in sockets 13 provided therefor in opposite sides of the claw 7 as clearly shown.

35 A salient feature of the present invention is in having the jaw 10 progressively decreasing in width from one side of the loop or yoke 11 to the opposite side thereof so that the working edge 14 which cooperates with the edge 9 of the claw 7 extends obliquely to present between the edges 9 and 14 a space 15 which progressively decreases 40 in width and which consequently serves to permit receiving between the edges 9 and 14 nail shanks of different diameter. Thus the tool is equipped for extracting or pulling nails of any suitable size or in other words for extracting or 45 pulling nails the shanks of which vary in diameter.

eter from a very small diameter to relatively large diameter.

The operation of the nail puller is thought to be apparent and may be briefly set forth as follows: the nail or spike is wedged between the 5 edges 9 and 14 of the claw 7 and jaw 10. In commencing to draw a nail or spike the bar 5 is held nearly vertical and after positive engagement has been made with the nail the handle 5 is then depressed or swung downwardly the face 10 8 acting as a fulcrum for the tool. It will thus be seen that with a tool of this character nails of varying sizes, weight, or shank diameters may be quickly and easily pulled or extracted.

Having thus described the invention what is 15 claimed as new is:—

1. A nail puller comprising a handle having a claw at one end provided with an end edge, a U-shaped yoke pivoted at one end to said claw and provided at its free end with a jaw adapted 20 to cooperate with said claw, the bight portion of said yoke progressively decreasing in width from one side to the other of said yoke to present a substantially diagonally disposed edge cooperable with the edge of said claw for accommodating 25 therebetween nails of varying shank diameters.

2. A nail puller comprising a handle provided with a claw at one end, a U-shaped yoke pivotally connected to the claw and provided with a 30 jaw adapted to coact with said claw, said yoke having parallel sides provided at one end with inwardly directed pins, and said claw being provided with sockets in opposite side edges thereof and in which said pins are journaled for pivotally connecting the yoke with said claw, the bight portion of said yoke being of progressively 35 varying diameter and cooperable with the edge of said claw for accommodating therebetween nails of varying shank diameters.

40 3. A nail puller comprising a handle having a claw at one end provided with an end edge, a U-shaped yoke pivoted at one end to said claw and provided at its free end with a jaw adapted to cooperate with said claw, the bight portion of 45 said yoke having one edge spaced from the end edge of the claw and inclined with respect to the claw to accommodate nail shanks of varying diameters.
